Attorney

UNITED STATES PATENT OFFICE.

PIERRE PAIRARD, OF PARIS, FRANCE.

ELECTRIC-WIRE CLAMP.

Application filed June 13, 1918. Serial No. 239,835.

To all whom it may concern:

Be it known that I, PIERRE PAIRARD, a citizen of the French Republic, residing in Paris, France, have invented certain new and useful Improvements in Electric-Wire Clamps, of which the following is a specification.

The present invention relates to an arrangement for fastening electric wires, characterized in that the conductor undergoes a progressive tightening by means of a cap nut screw on a threaded rod removably mounted on a resilient annular member placed on the insulator.

15 Fig. 1 is a side elevation showing one form of the improved attachment in place on the insulator.

Fig. 2 is an enlarged top plan detail with the nut removed,

20 Fig. 3 is a fragmentary sectional view showing the modified form of the nut with secondary clamping means,

Fig. 4 is a respective detail of still another form of the invention.

25 Fig. 5 is a vertical sectional detail of a further modification of the general form shown in Fig. 4, and

Fig. 6 is a side elevational view showing the forms shown in Figs. 4 and 5 applied to 30 an insulator.

Similar characters of reference are employed in all of the above described views to indicate corresponding parts.

Referring now, more particularly, to the drawings, especially to Figs. 1 to 3, the flexible collar 1 encompasses the trunconic head of an insulator. This collar is formed of a strip of hoop-iron wound over a mold of the same form as the insulators. The

40 ends of this strip are each provided with a notch, and the two tongues 3 thus formed are bent in the shape of a hook, so as to engage over a rod 4, which has projections 5 at its base and a notch 6, whose lateral

45 walls are planes forming a relatively small angle between them. The rod 4 is threaded and is provided with screw cap 7, which fastens the conductor 8 progressively and without cutting or shearing it, said conductor 8 being positioned in the notch 6.

In the modification represented in Figs. 4, 5 and 6 the collar 1 is hooked to a double

fork 10 having a threaded, non-slotted rod 11, on which is threaded a cross-shaped element 12, the arms of which form attaching grippers for the conductor 8', positioned against the rod 11. A cap screw 7', screwed on the rod permits of fastening the conductor 8' between the arms of the cross member 12 and the double forked member 10. 60

The cap screw of the two arrangements may be extended exteriorly by a threaded rod 13, 13' on which a knurled tightening nut 14, 14' is screwed as shown in Figs. 3 and 6. This arrangement permits of fastening, by means of nut 14, 14', either a connecting wire between two sections of a line whose ends are attached to two adjacent insulators supported by the same post, or a shunt or secondary wire connected to the 70 conductor 8.

These arrangements present the following advantages:

The attachment of the conductor, by the tightening of a nut, is simple and effective, 75 and owing to the V shape mounting, shearing of the wire is prevented since the wire only becomes distorted when the tightening is too great.

The contact between the conductor and the insulator is not such as with generally known insulators, but a large surface in which a large section of the insulating material is put under pressure.

Notwithstanding the cost of the collar 85 and of its attaching head, the present invention is a substantial economy by reason of the reduction of installation and maintenance cost.

Having now particularly described and ascertained the nature of my said invention and in what manner the same is to be performed, I declare that what I claim is:—

1. A clamp of the character described including an annular strap-like body portion having spaced hooks formed at the terminals and adjacent the side edges thereof, the hooks on one terminal extending in a direction opposite to those on the other terminal, a threaded stud the base of which is formed with opposed recesses the opposite side edges of which are embraced by opposed hooks of

95 100 the body portion and a clamping element embracing the stud.

2. A clamp as claimed in claim 1 wherein a cross-shaped plate having a central aperture and claw terminals is arranged on the stud beneath the clamping element with the 5 claw terminals embracing the hooks on the body portion and the head of the stud.

3. A clamp as claimed in claim 1 wherein

the clamping element is in the form of a closed end nut, a secondary stud connected in the outer closed end of the nut and a secondary clamping nut on the secondary nut for the purpose described. **10**

PIERRE PAIRARD.
